END SUPPORT FOR A GARMENT DISPLAY RACK

Maurice Cohen, 3580 NW. 52nd St.,
Miami, Fla. 33142

Filed Aug. 14, 1972, Ser. No. 280,583

Term of patent 14 years

Int. Cl. D20—02; D6—06
U.S. Cl. D6—85

FIG. 1

FIG. 2

FIG. 3

FIG. 4

FIG. 5

FIG. 1 is a perspective view of an end support for a garment display rack showing my new design;

FIG. 2 is a front elevational view thereof;

FIG. 3 is a side elevational view thereof;

FIG. 4 is a top plan view thereof; and

FIG. 5 is a bottom plan view thereof.

I claim:

The ornamental design for an end support for a garment display rack, substantially as shown.
